TOOL FOR REMOVING LAMP BASES

Jack Shapiro and Marvin Shapiro,
Bronx, N. Y.

Application March 4, 1947, Serial No. 732,276

5 Claims. (Cl. 81—3)

1

Our present invention relates to tools for removing the bases of electric lamps from electric sockets.

It is well known that considerable difficulty is frequently experienced by electricians and others in removing a lamp base from an electric socket due to corrosion of the base in its socket, particularly in out-door installations such as, for example, out-door electric signs and the lamp fixtures of theatres, and due to painting of indoor as well as out-door lamp fixtures. When a lamp burns out and the base thereof is stuck in its socket or when the glass bulb of the lamp is broken, removal of the base is a difficult and a time-consuming job. These difficulties and objections are eliminated by the tool of the present invention. Further, in accordance with one of the objects of this invention, the tool may be used for removing the bases of lamps of the pre-focussed type in which the base has a bayonet type of connection with its socket, or the tool may be used for removing the screw-threaded type bases from screw-threaded sockets, and where the diameters of lamp bases of either type are about the same, the same tool may be used for removing either type of lamp base from its socket.

Another object of the invention is the provision of a tool which is of simple construction, durable, and easy to operate.

The above and other objects, features and advantages of our invention will be fully understood from the following description considered in connection with the accompanying illustrative drawings.

In the drawings:

Fig. 1 is a side view of a tool embodying the present invention, showing the tool inserted in a lamp base of the pre-focussed type for removing such base from its socket;

Fig. 2 is a longitudinal sectional view of the tool;

Fig. 3 is a sectional view, on a larger scale, on the line 3—3 of Fig. 1;

Fig. 4 is a sectional view on the line 4—4 of Fig. 2, the lamp base gripping members being in projected position;

Fig. 5 is a side view of the end portion of the tool, the lamp base gripping members being in retracted position;

Fig. 6 is a plan view of a gripping member;

Fig. 7 is a view similar to Fig. 4, showing a modification or another form of the invention.

Referring now to the drawings in detail, the tool 10 embodying the present invention is made of steel or other suitable material and comprises

2

an operating member 12, a holder or support 14 and lamp base gripping members 16. As here shown operating member 12 is in the form of a rod and the support 14 is in the form of a sleeve 5 in which the operating member 12 is turnable about its longitudinal axis, the internal cylindrical surface 18 of the sleeve providing a bearing for the rod. The rod is provided with a handle 20.

Holder 14 has an enlarged internal circular end portion 22 and operating member 12 has an enlarged circular part 24 which is in fixed relation to said operating member and has a rotary fit in said end portion 22 of the holder and on the internal annular shoulder 26 of the latter. The edge surface portions 28 of the holder are flush with the outer surface of part 24, said surface of part 24 and surface portions 28 forming a slide bearing for gripping members 16. Diametrically opposite segmental portions 28 of holder 14 project outwardly beyond edge surface portions 26 and have confronting inner parallel edges 30 which form a guide groove for members 16, said edges 30 being slidably engaged by said members 16, respectively. An end closure member 32 having a flat inner surface is seated on the outer surfaces of portions 28 and is secured in that position by the peened over edges 34 of segmental portions 28. The inner surface of member 32 is 15 slidably engaged by the adjacent surfaces of gripping members 16, the latter being movable in opposite directions through the diametrically opposite openings 36 of the guide groove formed by edges 30. Said openings are defined by the edge surfaces 26 and by the confronting surface portions of member 32 together with the outer end portions of edges 30.

The gripping members 16 are moved transversely of operating member 12 and holder 14 by 20 suitable mechanism which is operable by turning member 12 in relation to holder 14. Said mechanism comprises crank pins 38 which are fixed to and project from end part 24 of said operating member and which engage the companion gripping members in transverse slots 40 thereof. The slot 40 of each gripping member is formed between the laterally projecting portions 42 which are spaced inwardly of the opposite end portions 44 of the gripping member. Said end portions 44 terminate in pointed ends 46 to provide a good purchase on the lamp base in the operation of the tool for turning the base in its socket. The side edges 48 of lateral portions 42 slidably engage the adjacent edge 30 of the guide groove 25 of the holder 14 and the two gripping members

are in slidable engagement with each other at their adjacent side edges 50.

Instead of the crank-pin mechanism provided in the tool for retracting and projecting the gripping members 16, any other suitable mechanism may be provided. In Fig. 7 there is illustrated an alternative mechanism which comprises a spur gear 52 on operating rod 12 and rack teeth 54 on the gripping members 16a which correspond to the gripping members 16.

The tool is preferably provided with releasable means for preventing relative turning movement of operating member or rod 12 and sleeve or holder 14 when the gripping members 16 (or 16a) are in their retracted positions, enclosed by the end portion of holder 14. The means provided for this purpose comprises releasable interengaging means on member 12 and holder 14. More particularly, a sleeve 56 is mounted on rod 12 for limited movement thereon longitudinally thereof and is held against turning movement on said rod by a cross pin 58 which engages said sleeve in motion-limiting opening 60. Sleeve 56 is provided with one or more projections 62 which are engageable in recesses 64, respectively, in the adjacent end portion 66 of holder sleeve 14. Sleeve 56 and holder portion 66 are preferably knurled.

In Fig. 1 the tool 10 is shown inserted in a lamp base B mounted in a known type of pre-focussed socket indicated more or less diagrammatically at S. The glass bulb of the lamp having been removed from the base, the end of the tool is inserted into the base with the gripping members 16 (or 16a) in their retracted positions so that they do not interfere with the insertion of the tool, sleeve 56 and end portion 66 of the holder being engaged with each other to prevent relative turning movement of operating member 12 and holder 14 and thus preventing projection of gripping members 16 during the operation of inserting the tool into the lamp base. When the tool has been inserted in the lamp base with the end of the tool properly positioned for engagement of the gripping members with the internal peripheral surface of the shell of the lamp base, as shown for example in Fig. 1, sleeve 56 is released from holder portion 66, and rod 12 is turned by means of its handle 20 for moving the gripping members 16 (or 16a) into engagement with said surface of the base. It will be observed that the gripping members move rectilinearly in opposite directions with respect to each other and that they move laterally of the tool so that one end of each gripping member is projected and disposed externally of the tool at a point substantially diametrically opposite the projected end of the other gripping member, while each gripping member has an end which is disposed within the tool. When the gripping members are in engagement with the lamp base, turning of rod 12 in the same direction in which it was turned for projecting the gripping members causes the lamp base to turn in its socket so that it may be removed therefrom.

In the type of pre-focussed lamp base and socket shown in Fig. 1, the rod 12 may be turned in either direction to disengage the spaced projections or flanges on the lamp base from the holding flanges on the socket and to position the base flanges in the spaces between the socket flanges so that the base can then be removed from the socket by axially withdrawing the base therefrom. However with bases and sockets of other specific types, the rod is turned in the proper direction required to effect removal of the base

from the socket. For example in using the tool to remove a screw threaded lamp base for a screw threaded socket, the rod 12 is turned in a counterclockwise direction (facing the socket) for engaging the gripping members with the base internally of the latter and for unscrewing the base from the socket shell. The ends of gripping members 16 (or 16a) are preferably serrated, for example as shown at 68 in Fig. 7, to provide a good grip of said members on the internal surface of the lamp base. It will be understood also that the serrated edges of said gripping members are advantageous when the tool is used for cleaning the cement, broken glass, etc. from the lamp base preliminary to the operation of the tool for removing the lamp base from the socket, and it will be observed that this cleaning operation may be performed by turning operating member 12 in either direction. As indicated in Fig. 1, member 56 is provided with rigid finger grips 70 so that the user of the tool may release said member from part 66 by pressing on said grips 70 toward handle 20 while the latter is in the user's hand. It will be understood that the tool may be made in a plurality of different sizes appropriate to lamp bases of different types and sizes.

Various changes in the details of construction and in the arrangement of parts may be made without departing from the underlying idea or principles of the invention within the scope of the appended claims.

Having thus described our invention, what we claim and desire to secure by Letters Patent is:

1. A tool for removing a lamp base from an electric socket, comprising an operating member, a supporting member on which said operating member is mounted for rotation, interengaging means on said members for preventing relative axial movement thereof, a pair of gripping members mounted on said supporting member for movement in relation thereto into and out of engagement with the lamp base internally thereof, said gripping members being movable rectilinearly in opposite directions laterally of said operating member from retracted positions to projected positions, and mechanism operable by turning of said operating member in relation to said supporting member to move said gripping members rectilinearly into and out of engagement with the lamp base, said mechanism comprising laterally spaced crank pins turnable with said operating member and said gripping members having recesses in which said pins engage said gripping members, respectively, for moving them rectilinearly, said supporting member having a part enclosing said gripping members in the retracted positions thereof and provided with openings through which said gripping members are movable, said supporting member having a transverse guide-groove in which said gripping members are movable and said gripping members having adjacent edges in slidable engagement.

2. A tool of the character described, comprising a sleeve, an operating rod mounted in said sleeve co-axially thereof for rotation therein in opposite directions, said sleeve having an end portion extending beyond the adjacent end of said rod, said end portion having diametrically opposed openings therein forming a through opening in said end portion of the sleeve, a pair of gripping members mounted adjacent said end of the rod for movement through said openings of the sleeve in opposite directions transversely of the rod axis, each gripping member having op-

posite gripping ends, one of which is movable outwardly through one of said openings and the other of which is movable outwardly through the other of said openings when said operating rod is moved in opposite directions, respectively, and interengaging parts on said rod and said gripping members, respectively, for moving one of said gripping members outwardly through one of said openings and the other gripping member outwardly through the other of said openings when said rod is turned about its axis in either direction.

3. A tool of the character described, comprising a sleeve, an operating rod mounted in said sleeve co-axially thereof for rotation therein in opposite directions, said sleeve having an end portion extending beyond the adjacent end of said rod, said end portion having diametrically opposed openings therein forming a through opening in said end portion of the sleeve, a pair of gripping members mounted adjacent said end of the rod for movement through said openings of the sleeve in opposite directions transversely of the rod axis, each gripping member having opposite gripping ends, one of which is movable outwardly through one of said openings and the other of which is movable outwardly through the other of said openings when said operating rod is moved in opposite directions, respectively, and interengaging parts on said rod and said gripping members, respectively, for moving one of said gripping members outwardly through one of said openings and the other gripping member outwardly through the other of said openings when said rod is turned about its axis in either direction, said interengaging parts comprising recessed portions in said gripping members and pins projecting from said end of the rod in laterally spaced relation offset laterally from the axis of said rod and engaging said gripping members, respectively, in said recessed portions thereof, respectively.

4. A tool for removing a lamp base from an electric socket, comprising an operating member, a supporting member on which said operating member is mounted for rotation, interengaging means on said members for preventing relative axial movement thereof, a pair of gripping members mounted on said supporting member for movement in relation thereto into and out of engagement with the lamp base internally thereof, said gripping members being movable rectilinearly in opposite directions laterally of said operating member from retracted positions to projected positions, each of said gripping members having gripping portions at their opposite ends, and mechanism operable by turning of said operating member in relation to said supporting member to move said gripping members rectilinearly into and out of engagement with the lamp base, said mechanism comprising parts

carried by and turnable with said operating member and said gripping members having recessed portions in which said mechanism parts engage said gripping members, respectively, for moving the latter rectilinearly, said supporting member having a pair of diametrically opposed openings through which oppositely disposed end portions of said gripping members, respectively, are moved to their said projected and retracted positions 10 when said operating member is turned in either direction.

5. A tool for removing a lamp base from an electric socket, comprising an operating member, a supporting member on which said operating member is mounted for rotation, interengaging means on said members for preventing relative axial movement thereof, a pair of gripping members mounted on said supporting member for movement in relation thereto into and out of engagement with the lamp base internally thereof, said gripping members being movable rectilinearly in opposite directions laterally of said operating member from retracted positions to projected positions, each of said gripping members having gripping portions at their opposite ends, and mechanism operable by turning of said operating member in relation to said supporting member to move said gripping members rectilinearly into and out of engagement with the lamp base, said mechanism comprising parts 15 carried by and turnable with said operating member and said gripping members having recessed portions in which said mechanism parts engage said gripping members, respectively, for moving the latter rectilinearly, said supporting member having a pair of diametrically opposed openings through which oppositely disposed end portions of said gripping members, respectively, are moved to their said projected and retracted positions 20 when said operating member is turned in either direction.

6. A tool for removing a lamp base from an electric socket, comprising an operating member, a supporting member on which said operating member is mounted for rotation, interengaging means on said members for preventing relative axial movement thereof, a pair of gripping members mounted on said supporting member for movement in relation thereto into and out of engagement with the lamp base internally thereof, said gripping members being movable rectilinearly in opposite directions laterally of said operating member from retracted positions to projected positions, each of said gripping members having gripping portions at their opposite ends, and mechanism operable by turning of said operating member in relation to said supporting member to move said gripping members rectilinearly into and out of engagement with the lamp base, said mechanism comprising parts 25 carried by and turnable with said operating member and said gripping members having recessed portions in which said mechanism parts engage said gripping members, respectively, for moving the latter rectilinearly, said supporting member having a pair of diametrically opposed openings through which oppositely disposed end portions of said gripping members, respectively, are moved to their said projected and retracted positions when said operating member is turned in either direction.

7. A tool for removing a lamp base from an electric socket, comprising an operating member, a supporting member on which said operating member is mounted for rotation, interengaging means on said members for preventing relative axial movement thereof, a pair of gripping members mounted on said supporting member for movement in relation thereto into and out of engagement with the lamp base internally thereof, said gripping members being movable rectilinearly in opposite directions laterally of said operating member from retracted positions to projected positions, each of said gripping members having gripping portions at their opposite ends, and mechanism operable by turning of said operating member in relation to said supporting member to move said gripping members rectilinearly into and out of engagement with the lamp base, said mechanism comprising parts 30 carried by and turnable with said operating member and said gripping members having recessed portions in which said mechanism parts engage said gripping members, respectively, for moving the latter rectilinearly, said supporting member having a pair of diametrically opposed openings through which oppositely disposed end portions of said gripping members, respectively, are moved to their said projected and retracted positions when said operating member is turned in either direction.

8. A tool for removing a lamp base from an electric socket, comprising an operating member, a supporting member on which said operating member is mounted for rotation, interengaging means on said members for preventing relative axial movement thereof, a pair of gripping members mounted on said supporting member for movement in relation thereto into and out of engagement with the lamp base internally thereof, said gripping members being movable rectilinearly in opposite directions laterally of said operating member from retracted positions to projected positions, each of said gripping members having gripping portions at their opposite ends, and mechanism operable by turning of said operating member in relation to said supporting member to move said gripping members rectilinearly into and out of engagement with the lamp base, said mechanism comprising parts 35 carried by and turnable with said operating member and said gripping members having recessed portions in which said mechanism parts engage said gripping members, respectively, for moving the latter rectilinearly, said supporting member having a pair of diametrically opposed openings through which oppositely disposed end portions of said gripping members, respectively, are moved to their said projected and retracted positions when said operating member is turned in either direction.

9. A tool for removing a lamp base from an electric socket, comprising an operating member, a supporting member on which said operating member is mounted for rotation, interengaging means on said members for preventing relative axial movement thereof, a pair of gripping members mounted on said supporting member for movement in relation thereto into and out of engagement with the lamp base internally thereof, said gripping members being movable rectilinearly in opposite directions laterally of said operating member from retracted positions to projected positions, each of said gripping members having gripping portions at their opposite ends, and mechanism operable by turning of said operating member in relation to said supporting member to move said gripping members rectilinearly into and out of engagement with the lamp base, said mechanism comprising parts 40 carried by and turnable with said operating member and said gripping members having recessed portions in which said mechanism parts engage said gripping members, respectively, for moving the latter rectilinearly, said supporting member having a pair of diametrically opposed openings through which oppositely disposed end portions of said gripping members, respectively, are moved to their said projected and retracted positions when said operating member is turned in either direction.
